(57) **CLAIM**

We claim the ornamental design for a microphone with fold-up legs, as shown and described.

DESCRIPTION

FIG. 1 is a perspective view of a microphone with fold-up legs with the legs in a folded position,

FIG. 2 is a front view thereof,

FIG. 3 is a left-side view thereof,

FIG. 4 is a right-side view thereof,

FIG. 5 is a rear view thereof,

FIG. 6 is a top view thereof, and

FIG. 7 is a bottom view thereof; and

FIG. 8 is a perspective view of a microphone with fold-up legs with the legs in an un-folded position,

FIG. 9 is a front view thereof,

FIG. 10 is a left-side view thereof,

FIG. 11 is a right-side view thereof,

FIG. 12 is a rear view thereof,

FIG. 13 is a top view thereof; and,

FIG. 14 is a bottom view thereof.

The broken lines shown do not form part of the claimed design.
